UNITED STATES PATENT OFFICE.

ARTHUR E. SMALL, OF OAK PARK, ILLINOIS, ASSIGNOR TO UNION METAL PRODUCTS COMPANY, OF CHICAGO, ILLINOIS, A CORPORATION OF DELAWARE.

CENTERING DEVICE FOR CAR COUPLERS.

Application filed November 12, 1925. Serial No. 68,663.

The invention relates to devices for retaining a railway car coupler adjacent the longitudinal center line of the car. Such a device assures proper coupling and transmits the impact blow, due to the coupling of the cars, directly to the coupler shank and to the draft gear without causing lateral stress in the coupler head or shank, thus reducing broken coupler knuckles and guard arms. Such a device eliminates the necessity of trainmen going between the cars to move the coupler to such a position that it will couple upon impact with another coupler. This feature reduces accidents to trainmen and also minimizes the time required to couple cars.

In the drawings:

The left half of Fig. 1 shows a part of a railway car with my device applied thereon. The right half of Fig. 1 shows a section on line 1—1 of Fig. 2.

Fig. 2 shows a side elevation of Fig. 1.

Fig. 3 is similar to the right half of Fig. 1 and shows the coupler out of normal position.

The striking casting 1 is attached to the center sills 2 in the usual manner and is provided with a tread 3. The coupler 4 rests upon the carriage 5 and is held in the proper relative position thereto by the lugs 6. An eccentric wheel 7 is pivoted (8) to the carriage 5 to roll upon the tread 3 of the striking casting 1. In normal position, as shown in Fig. 1, the center 9 of the radius 10 of the tread wheel is directly above or in vertical alignment with the pivot point 8 of the wheel.

When the coupler (and carriage 5) moves laterally in either direction the wheel 7 assumes the position similar to that shown in Fig. 3 so that the contacting surface of the wheel with the striking casting is not in vertical alignment with pivot 8 (it must necessarily be in vertical alignment with point 9) so that the eccentric load of the coupler and its associated parts tends to return the wheel to its normal position and to carry the carriage with it; in other words, return the coupler to the longitudinal center of the car.

The tread on the striking casting may be provided with a rack and the eccentric wheel

may be provided with teeth which engage the rack to prevent slippage. Any other means to prevent slippage between the treads and the wheel be employed and still come within the broader claims of this invention.

When teeth are used, as above described and illustrated, their depth is made greater than the vertical distance between the top of the coupler and the underside of the striking casting so that when the device is assembled and the coupler is in position thereon, it is impossible for the carriage to move upwardly far enough to permit the teeth of the wheel to become disengaged from the rack on the striking casting.

In the preferred form two wheels are employed positioned equi-distant on either side of the center line of the coupler. However, only one wheel may be used at one end of the carriage to return the coupler to its central position and any convenient means used to support the opposite end of the carriage or a single wheel may be positioned adjacent the center of the car and the extremities of the carriage otherwise supported to prevent the device from tipping.

I claim:

1. A centering device for a car coupler comprising a member provided with a tread, a coupler carriage, and an eccentric wheel pivoted to said carriage to roll upon said tread.

2. A centering device for a car coupler comprising a member provided with a tread, a coupler carriage, and an eccentric wheel pivoted to said carriage to roll upon said tread and positioned with the center of the radius of the wheel in vertical alignment with the pivot of the wheel.

3. A centering device for a car coupler comprising a member provided with a tread, a coupler carriage, an eccentric wheel pivoted to said carriage to roll upon said tread, and means to prevent slippage between said wheel and said tread.

4. A centering device for a car coupler comprising a member provided with a rack, a coupler carriage, and an eccentric gear wheel pivoted to said carriage to engage said rack.

ARTHUR E. SMALL.
